UNITED STATES PATENT OFFICE.

OVERTON WINSTON, OF MINNEAPOLIS, MINNESOTA.

HEADLIGHT.

1,280,926.

Specification of Letters Patent.

Patented Oct. 8, 1918.

Application filed May 1, 1916. Serial No. 94,617.

To all whom it may concern:

Be it known that I, OVERTON WINSTON, a citizen of the United States, residing at Minneapolis, in the county of Hennepin and State of Minnesota, have invented certain new and useful Improvements in Headlights; and I do hereby declare the following to be a full, clear, and exact description of the invention, such as will enable others skilled in the art to which it appertains to make and use the same.

My present invention relates to headlights, such as used in automobiles, and has for its object to provide certain improvements in the lamp socket thereof. Particularly, the invention is in the nature of an improvement on or modification of the lamp socket construction disclosed and claimed in my pending application S. N. 86,851 filed of date, March 27th, 1916, and entitled "Headlights".

In the accompanying drawings which illustrate the invention, like characters indicate the like parts throughout the several views.

Referring to the drawings:

Figure 1 is a vertical section taken through the improved socket showing an electric light bulb held thereby;

Fig. 2 is a section on the line $x^2 x^2$ of Fig. 1;

Fig. 3 is a view corresponding to Fig. 1, but illustrating a slightly modified construction; and

Fig. 4 is another view corresponding to Fig. 1, but showing a socket designed for a three-contact lamp or light bulb.

Figs. 1, 2 and 3 show the socket designed for a two contact lamp or light bulb. Referring first to the construction illustrated in Figs. 1 and 2, the numeral 1 indicates diagrammatically an electric light bulb preferably of well known Ediswan single-base type, but, of course, other types may be employed. As shown, this bulb has a hood contact sleeve 2 and an axial contact disk 3. The sleeve 2 is adapted to be telescoped into a holding collar 4 that is provided with an externally threaded eccentric portion 5 that performs a highly important function preferably to be noted, but fully described and claimed in my said application above identified.

The metallic collar 2 of the bulb is provided with a plurality, as shown, with two radially projecting lugs 6 adapted to be in-

serted through a corresponding pair of internal longitudinal grooves 7 formed in the collar 4. At the inner extremities of the grooves 7, the collar 4 is provided with an internal shoulder formed with corrugations or serrations 8 with which the lugs 6 are adapted to be engaged. The said grooves 7 and corrugated shoulder 8 are more fully described in my said prior application, and are indicated by dotted lines in Fig. 1.

The eccentric externally threaded portion 5 of the holding collar 4 is screwed into the internal threads 9 of a socket sleeve 9, in the rear end of which is secured an insulating plug 10. The insulating plug 10 has a forwardly spring-pressed axially projecting contact plunger 11, the head of which engages the axial contact 3 of the light bulb, when the latter is in position. The so-called holding collar 4 and sleeve 9 constitute an adjustable lamp socket, and by rotary adjustment of the said collar and its threaded eccentric, the light bulb may be adjusted, both longitudinally and transversely of the axis of the socket, and hence, of the reflector, not shown, but which will usually be employed in headlights where the socket is applied.

To prevent rattling, and to frictionally hold the eccentric collar in its different set adjustments, a coiled spring 12 is placed within the sleeve 9 and is compressed between the insulating block 10 and the inner end of the eccentric end portion of the holding collar. The spring 12 is thus brought into close association with the internal threads 9 of the sleeve 9, and, in practice, will frequently be in contact therewith. In practice, I have found that where threads 9 and a spring 12 have the same spiral thread, that is, for example, when both have a right hand travel, the said spring will frequently catch in the said threads and will interlock and thus interfere with proper adjustments of the holding collar; but I have also found that by giving the said threads and spring reverse spiral travel, that is, for example, by making the one right hand and the other left hand, this interlocking will be positively prevented. This reverse arrangement of the threads and spring is clearly shown in Fig. 1. To prevent the front end of the spring 12 from catching in the threads 9, it is bent or turned inward at 12^a (see Fig. 2).

In the single-base lamp or light bulb shown in Fig. 1, the contact plunger 11 is

connected to one of the lamp circuit leads 13, and through the same and contact disk 3, to one of the electrodes of the lamp filament, not shown. The other electrode of the lamp 5 filament is grounded through the sleeve 2, collar 4 and sleeve 9 and is connected to the other lamp lead 14.

The internal thread 9^a is terminated at its 10 inner portion at such distance from the front end of the plug 10, that the spring 12 will not compress solid even when the threaded eccentric 5 is screwed into the socket sleeve 9 as far as it will go. This prevents the elasticity of the spring from being destroyed 15 by over-compression of the spring.

The construction illustrated in Fig. 3 is like that illustrated in Fig. 1, except that the insulating plug 10^a has a reduced forwardly projecting portion 10^b around which 20 the rear end of the spring 12 is telescoped. This reduced portion 10^b permits the use of a longer spring than that employed in the construction illustrated in Fig. 1. As already stated, the sockets shown in Figs. 1 25 and 3 are especially designed for single-base light bulbs. Preferably, both of these sockets would be mounted for pivotal adjustments, and this may be done by the construction illustrated in my said prior application.

The socket shown in Fig. 4 is especially 30 designed for a double base light bulb, such, for example, as that illustrated in my pending application S. N. 91,226, filed of date, April 14, 1916, and entitled "Headlights." A lamp of this kind has three electrical 35 contacts 15, 16 and 17. The contact 15 is in the form of a metallic sleeve which surrounds the shank of the lamp, the contact 40 16 is in the form of a metal ring applied to the end of the shank, and the contact 17 is in the form of a small disk located at the axis of the shank. The said contacts 15, 16 and 17 are insulated from each other by the 45 insulating material of which the shank is made. In this socket, the elements 4, 5, 9, 10, 11 and 12 are identical with the parts identified by like numerals in Fig. 1. In 50 this arrangement, however, a coiled contact spring 18 is compressed between the insulating block 10 and the contact ring 16. This spring 18 constitutes a part of one of the electrical connections, and it is electrically connected to one of the lamp leads 19. The 55 said spring 18 must, of course, be held out of contact with the spring 12, and also out of contact with the contact plunger 11 and its spring. This is done by means of an insulating ring 20, the outer surface of which 60 is tapered and driven into the cavity formed within the eccentric 5. As illustrated, the said ring 20 is held in the eccentric only by friction, but if desired it may be otherwise secured thereto.

65 Here it should be noted that the cavity

within the said eccentric 5 is concentric to the axis of the shank of the light bulb and to the axis of the contact ring 16, but is eccentric to the axis of the contact plunger 11. Under rotary adjustments of the collar 4 70 and its eccentric 5, the front end of said spring 18 will be kept concentric to and in contact with the contact ring 16.

The head of the said contact plunger 11 is so extended that it will always maintain 75 its engagement with the contact disk 17, regardless of the shifting movements of the latter, in respect thereto. The insulating ring 20 is internally tapered and the front end portion of the contact spring 18 is also 80 slightly tapered so that when the lamp is removed, said insulating ring will serve as a stop to prevent the spring from being projected out at the socket. A socket such as shown in Fig. 4 will not usually be pivotally 85 mounted, because with a two-filament lamp, the variable projection of the light beams is produced by directing the current through one or the other of the two filaments of the lamp.

90 What I claim is:

1. A lamp socket having internally and externally threaded engaging members and a spring within the internally threaded member closely associated with the threads 95 thereof and pressing against the externally threaded member, the said internal threads and spring having reverse travel to prevent interlocking thereof.

2. In a lamp socket, the combination with 100 an internally-threaded sleeve having an insulating block in one end, of a lamp holding collar having an externally threaded eccentric engaging the internal threads of said sleeve, and a spring within said sleeve 105 closely associated with the threads thereof, and compressed between said insulating block and externally threaded eccentric, said spring and the internal threads of said sleeve having reverse travel.

3. A lamp socket having internally and externally threaded engaging members and a spring within the internally threaded member closely associated with the threads 115 thereof and pressing against the externally threaded member, the said internal threads and spring having reverse travel to prevent interlocking thereof, the end of said spring being inwardly curved to prevent the same from catching in the said internal threads. 120

4. In a lamp socket, the combination with an internally-threaded sleeve having an insulating block in one end, of a lamp holding collar having an externally threaded eccentric engaging the internal threads of 125 said sleeve, and a spring within said sleeve closely associated with the threads thereof, and compressed between said insulating block and externally threaded eccentric, said spring and the internal threads of said 130

- sleeve having reverse thread or travel, the eccentric engaging end of said spring being inwardly curved to prevent the same from catching in said internal threads.
- 5 5. The combination with a socket sleeve having an insulating block in one end, and having internal threads in its other end, of a lamp holding collar having an externally threaded eccentric engaging the internal
10 threads of said sleeve, an axial spring-pressed contact plunger projecting from said insulating block, an insulating ring inserted into said threaded eccentric, and a contact spring seated at its rear end against
- said insulating block, and at its forward 15 end projecting through said insulating ring for engagement with one of the lamp shank contacts, and a tension spring surrounding said contact spring and insulating ring and compressed between said insulating block 20 and the inner portion of said eccentric.

In testimony whereof I affix my signature in presence of two witnesses.

OVERTON WINSTON.
